UNITED STATES PATENT OFFICE.

ALBERT J. LOEPSINGER, OF PROVIDENCE, RHODE ISLAND, ASSIGNOR, BY MESNE ASSIGNMENTS, TO GENERAL FIRE EXTINGUISHER COMPANY, OF PROVIDENCE, RHODE ISLAND, A CORPORATION OF DELAWARE.

AUTOMATIC SPRINKLER.

Application filed April 7, 1922. Serial No. 550,304.

This invention relates to automatic sprinklers. More particularly it relates to devices for improving upon fusible solder as a releasing device by providing a glass or other 5 frangible strut for holding the sprinkler normally closed, and for releasing its valve when heated by a fire. The most practicable method thus far proposed for doing this with precision on a commercial scale, is to make the 10 strut hollow and to fill it with a liquid associated usually with a gas or vapor whose expansion will shatter the strut when the predetermined operating temperature is reached. In such cases the glass strut is a sealed bulb 15 but the making of this bulb so that its fracture will occur with the necessary shattering action and with the desired certainty, is a matter of much difficulty. As the bulb hitherto has constituted the strut, its walls 20 have had to be rather thick. The thickness both makes the glass harder to shatter, and, somewhat contrarily, makes it more likely to shatter prematurely. The latter difficulty results from the internal stresses that are set up 25 within the glass, in its cooling from the sealing operation, where nearby portions of the glass are respectively at the low temperature of liquefaction of the contents, and at the high temperature of plasticity of glass. It 30 is among the objects of the present invention to reduce these various difficulties and to improve the situation in other respects. This is accomplished by making separate containers, one of which serves as the strut, and is not 35 subject to internal stresses due to cooling from the sealing; and the other of which serves only as the container for the expansible liquid and can therefore be made in any of various more desirable shapes, sizes and arrangements. As the whole of the material 40 for causing the fracture is contained within the bulb, the space surrounding it within the strut may either be empty or may be provided with a superior heat absorbing and conduct- 45 ing material for carrying a rise of temperature rapidly into the walls of the internal container. Moreover those walls of the internal container may be placed so close to the walls of the strut that there is little delay in 50 transmission of heat. Furthermore they may be shaped so that the fracturing agent is set so far apart from the valve that the cooling effect of water in the sprinkler system

does not counteract heat that may be received from the surrounding atmosphere 55 when a fire occurs. Furthermore it becomes possible by this arrangement to provide a metallic external device for conducting heat the more rapidly into the interior of the strut, for transmission to the frangible member 60 which contains the active agent. Moreover, as the strut member no longer has to resist expansive forces, but stands always under longitudinal compression, it can be designed so as to be very easily frangible by a lateral or 65 bending stress, thus making possible a reduction of the quantity fracturing agent and of the size of its container, with consequent possible reduction of diameter of the tubular strut. 70

All of these features, or such of them as it may be desired to employ in combination, tend toward improvement in automatic sprinklers in the direction of certainty of action; quickness of response, when the predetermined temperature is reached; reliability, in not going off too soon, and precision of temperature of action; and the accomplishing of these results with a minimum of material in 80 strut and contents. An incidental feature 80 of the invention is the providing of means for collecting and conducting heat from an area at a little distance from the fracturing agent, to raise its temperature the more quickly when the regional temperature rises; and this 85 means may subsequently act as a deflector of the fire-extinguishing agent discharging from the sprinkler. Other objects such as means for ready adjustment of the several parts, the provision of heat-insulating material to prevent loss of effective heat, and the arrangement and construction of the various elements will be set forth as the description 90 develops.

These objects are attained by providing a 95 tubular strut of frangible material for transmitting the holding force of the yoke to the valve, there being a suitable heat-gathering plate or deflector arranged at the yoke end of this strut to overhang it, so that the gathering of heat and its flow into upper end is 100 expedited, so far as the quickness with which contents approach the temperature of the surrounding air is concerned. Within this tube is a container for the whole of the fracturing agent, in the shape of a relatively small 105

bulb with elongated neck. The neck may serve as the supporting standard of the container, in that its end rests on the valve. The bulb is of a diameter closely approximating 5 the diameter of the tubular cylinder surrounding it, so that but little space exists between the circumference of the bulb's body and the cylindrical wall, thereby facilitating the transfer of heat from one to the other. 10 And by virtue of the extended neck, the bulb is at that end of the strut chamber which is in proximity to the heat gathering plate. Because of the nearness of the body end, which contains most of the expansible fluid, 15 to the heat gathering plate, and the relative size of the bulb to the cylinder, the empty space in the latter is not objectionable; but it is a further feature that this space may be filled with a quantity of good heat conducting 20 material. A block of heat-insulating material may be placed between the heat gathering plate and an adjusting screw threaded through the apex of the yoke. This screw affords a ready means for setting the 25 valve in a desired position under such pressure as may be needed. The sprinkler may be equipped with the ordinary fluid deflector at its top, or the heat gathering plate may be so constructed as to serve a double function, 30 namely, concentrating the heat prior to the opening of the sprinkler, and spreading the discharge of the fire-extinguishing agent therefrom after the sprinkler opens. It is intended that the patent shall cover, by suitable 35 expression in the appended claims, whatever features of patentable novelty exist in the invention disclosed.

In the drawings:

Figure 1 is an elevation in medial section 40 of an automatic sprinkler embodying the invention showing the arrangement and relation of the frangible members, and the heat-gathering plate;

Figure 2 is a similar view, showing the 45 plate modified to serve also as a deflector, and showing the space between the frangible members filled with heat-conducting material; and

Figure 3 is a cross section through the strut 50 and bulb as on line 3-3 of Figure 1, showing a shape of strut that may be employed.

Referring to the drawings, the sprinkler shown embodies a body portion 1 having a frame 2 preferably screwed into the body portion. A flexible diaphragm 3 having a central opening therein, and properly secured in place, preferably by clamping the outer edge thereof between the body portion 1 and the frame 2, carries the seat 4 for the 55 valve 5. This valve 5 is preferably made of non-corrosive material, and a metal cap 6 rests thereon.

A frangible member 7, constituting a strut, 60 preferably made of glass and in tubular form, 65 has one end bearing against the metal cap 6.

Bearing against the opposite end of said frangible strut is a metallic plate 8 preferably disk-shaped, as shown. When the valve-seat is formed upon or carried by a flexible diaphragm as shown, the metallic plate 8 may 70 be constructed and arranged to engage directly with the frame 2, said metallic plate and the frangible member 7 constituting a strut interposed between the valve and the frame to hold the valve to its seat. 75

In the construction shown, however, an adjusting screw 9 is employed, the outer end of the frame being provided with a screw-threaded boss 10 to receive the same. Preferably a block of heat-insulating material 11 80 is placed between the metallic plate 8 and the end of the adjusting screw. As shown in Figure 1, the deflector 12 is secured to the adjusting screw 9 on the outside of the frame 2, and so that said adjusting screw may be 85 turned by turning the deflector. When the valve has been properly adjusted to its seat the adjusting screw may be held in its adjusted position by a cross-pin 13 passed through said screw and the boss 10. 90

A second frangible member 14, constituting a container for the fracturing agent, preferably in the form of a glass bulb having an elongated neck 15 is located within the frangible member 7. The neck 15 is preferably 95 made of considerable length as shown, as this facilitates the proper filling and sealing of the frangible member 14, and provides so that its body or bulb portion may be positioned at or near that end of the frangible strut 7 100 at which the metallic plate 8 is located and so that the heat from said plate will the more readily and quickly reach said bulb and affect the whole of its contents.

Referring now to Figure 2, the sprinkler 105 therein shown is the same in its general construction as the sprinkler shown in Figure 1. The metallic plate 8^a is made in the form of a deflector and is secured to the inner end of the adjusting screw 9^a, which may be 110 turned by means of the plate to adjust the valve to its seat. When the valve has been properly adjusted the screw may be held in its adjusted position by a cross-pin 13.

In this construction the block of insulating 115 material may be omitted, as there is placed in the space between the frangible tubular strut 7 and the frangible container 14 and plate 8^a, a quantity of heat-conducting material 16, which may consist of metal filings, graphite, 120 or other suitable material. It is preferable to fill this space completely with the heat-conducting material, as this facilitates the conduction of heat to the inner frangible vessel, but if desired a lesser quantity of conducting 125 material may be employed and the space only partially filled therewith.

The frangible vessel 14, containing the expansive contents, has nothing to do with holding the valve closed and is therefore en- 130

tirely free from compressive stress the valve being held closed solely by the frangible strut 7 and the parts cooperating therewith. As the frangible container 14 is thus entirely free 5 from said stress the walls thereof may be made relatively thin, which not only serves to expedite the breaking or bursting of said frangible member by the expansion of its contents, but also results in a greater uniformity 10 in the thickness of the walls and lessens or eliminates the probability of internal stresses arising from its manufacture and sealing.

By the employment of a separate frangible member for holding the valve closed such 15 member may be made or designed to resist end pressure as a strut and to break easily under lateral pressure. It may be made in the form of a cylinder, as shown, thereby providing relatively great strength in such valve- 20 holding member and one which will readily withstand any strain to which it may be subjected. Moreover, as this valve-holding frangible member may thus be of a simple cylindrical form, such member may be readily 25 moulded, and may thus, if desired, be made of some frangible material other than glass. And it may have the combination of strut strength and weakness in bending stresses indicated at 7' in Figure 3.

30 When the sprinkler is subjected to the action of the requisite amount of heat, which may be determined by the character of the contents of the frangible member 14, the expansion of such contents will burst the frangible members 14 and 7, thereby releasing the valve and letting the sprinkler open.

It is preferred that the character of the 40 contents of the frangible member 14 shall be such that when said member is fractured by the expansion of such contents an explosion will take place, as by such explosive action the shattering of both of the frangible members and the dislodgment of the valve-holding member, and the consequent release of the 45 valve, is rendered more certain. To that end the contents may be as explained in the United States patents granted to me Nos. 1,290,602 and 1,290,762.

As will be understood, the employment of 50 the metallic plate 8 serves to collect the heat and conduct the same to the frangible members and to the contents of the frangible member 14, thereby facilitating the expansive or explosive action of such contents.

55 In the construction shown in Figure 1 when the valve-holding frangible member 7 is shattered or dislodged the metallic plate 8 is released and thrown out, and the water issuing from the opened nozzle is deflected and distributed by the deflector 12. In the construction shown in Figure 2 the metallic plate 8^a performs not only the function of collecting and conducting heat to the frangible member, but also the function of a deflector when the 60 sprinkler opens, said plate being properly

formed to act as such deflector and being secured to the frame of the sprinkler for this purpose.

The separation of the strut member from the bursting member not only permits the use 70 of a bursting member which is smaller than it could be if the strut were the container of the bursting charge, it also affords other advantages. Among these are that the container can be made globular, or substantially 75 so, of approximately the diameter of the interior of the strut. It follows that the body of contents is, or may be, concentrated at a distance from the water cooled valve; that it is, or may be, close to the thermally sensitive 80 heat gathering plate 8 or 8^a which keeps it in harmony with external air, as regards temperature, and its bursting force is concentrated at one place on the strut. This last is especially true if the remaining space in the tubular strut is filled with a solid material as in 85 Figure 2.

I claim as my invention:

1. An automatic sprinkler embodying a nozzle, a deflector, and a frangible container, 90 adapted to release the sprinkler by bursting from expansion of material within it when heated; combined with a plate of good heat conducting material supported by said container, extending outward from close proximity to said container, arranged with a relatively large exposed surface to receive heat rapidly and adapted to conduct such heat to the container and to fall out of the path of the spray from the nozzle upon fracture of said 95 container.

2. An automatic sprinkler embodying a nozzle, a deflector, and a frangible member containing expansive material adapted to break said member when heated, thereby to release the sprinkler; and a plate of good heat conducting material arranged in proximity to said frangible member supported thereby and extending radially from the axis in all directions beyond it, whereby high temperature 105 in the adjacent region is quickly transmitted to said member and adapted to fall out of the path of the spray from the nozzle upon fracture of said frangible member.

3. An automatic sprinkler embodying a 110 nozzle, a deflector, and a frangible member containing expansive material; a second frangible member comprising an open ended tube surrounding it and constituting a strut holding the sprinkler closed; a plate of heat 120 conducting material reaching out from the end of the tube into the region around said frangible members and adapted to fall out of the path of the spray from the nozzle upon fracture of said tube; and heat conducting 125 material within the tube.

4. An automatic sprinkler embodying, for holding its valve closed, a frangible strut adapted by its shape to resist compression 130 stresses in the direction of its axis relatively

strongly and having a weaker wall portion, adapted to break relatively easily under transverse stress, combined with a container and contents adapted to burst on being heated 5 and arranged in relation to said strut in position to apply a transverse stress thereto upon bursting.

5. An automatic sprinkler embodying, for holding its valve closed, a tubular frangible 10 strut, having thin portions in its wall extending in the direction of its axis, whereby the strut is made relatively weak against stresses transverse to its axis, combined with heat re-

sponsive means within the strut adapted to apply a transverse stress thereto when heated. 15

6. An automatic sprinkler embodying, for holding its valve closed, a cylindrical strut of frangible material, having grooves along its surfaces in the direction of its axis whereby it is made relatively weak against trans- 20 verse stresses, combined with heat responsive means within the strut adapted to apply a transverse stress thereto when heated.

Signed at Providence, Rhode Island, this 4th day of April, 1922.

ALBERT J. LOEPSINGER.
